UNITED STATES PATENT OFFICE

2,501,843

FOLDING BASKET FOR MARKET CARRIERS

George W. Concklin, Suffern, N. Y., assignor to
 John Chatillon & Sons, New York, N. Y., a corporation of New York

Application November 15, 1946, Serial No. 710,057

2 Claims. (Cl. 220—6)

1

The invention relates to folding baskets for market carriers or wheeled carts such as are commonly employed nowadays in chain grocery stores, so-called super-markets and other self-service stores. It is particularly applicable for use in conjunction with market carriers which can be folded so as to occupy a minimum space when not in use.

In stores which provide carrier carts for the convenience of customers in assembling and carrying their purchases to the wrapping counter or cashier's station, it is customary to keep the carriers with empty baskets near the store entrance where the customer takes one upon arrival and wheels it around like a baby buggy. The empty carriers and baskets take up considerable space, frequently getting in the way of customers as they arrive and hampering trade at nearby counters through obstruction of the aisles. It is an object of the present invention to alleviate this difficulty by providing an improved form of folding basket which is especially adapted for use in conjunction with folding carts and which, in its collapsed condition, will occupy a minimum space.

It is also a particular object of my invention to provide a collapsible basket which has telescoping sides, the several sections of which will nest completely within one another so as to fold entirely flat and thus occupy only a small fraction of the space required for the open basket. I am aware that collapsible baskets have been made heretofore, but it has been an object of my invention to provide an improved construction which will fold flatter and which is generally more simple and compact than any basket which has been devised before.

These and other objects and advantages of my invention will appear more fully as the description proceeds.

In the drawings, Figs. 1 to 3 illustrate a preferred embodiment of my invention, Fig. 1 showing the basket in central longitudinal vertical cross-section, Fig. 2 being a transverse sectional view taken as indicated at 2—2 in Fig. 1, and Fig. 3 being a detail cross-sectional view showing to an enlarged scale the lower left-hand corner of Fig. 2 with the basket collapsed.

Figs. 4 to 6 show a modified basket construction, Fig. 4 being a central longitudinal vertical cross-section, Fig. 5 being a transverse sectional view taken as indicated at 5—5 in Fig. 4, and Fig. 6 being an enlarged detail cross-sectional view showing the lower left-hand corner of Fig. 5 with the basket collapsed.

2

The basket in its general arrangement comprises a bottom 7, end members 8 hingedly mounted in association with the bottom as at 9, and a series of horizontal side members 10 arranged in substantial parallelism at each side of the basket, the side members being pivotally secured individually to the sides of end members 8 as at 11. An important feature of the construction resides in forming the end members 8 with their sides 12 (Fig. 2) inclined upwardly and outwardly so as to be of progressively increasing width from bottom to top. Thus the lateral spacing of successive pairs of side members at opposite sides of the basket increases from bottom to top to form upwardly and outwardly inclined sides, so that when the end members are folded down into collapsed position the side members 10 can be brought into overlapping or telescoped relationship as clearly shown in Fig. 3. The basket can be folded by moving the right-hand end member 8 (as viewed in Fig. 1) about its pivot 9 in the direction indicated by the arrow a. Or if desired the left-hand end member 8 can be folded inwardly, i. e. the basket can be collapsed in either direction as may be desired.

If desired, the bottom 7 may be perforate as indicated in the drawings, or it can be made of expanded metal or of a solid metal sheet. In the construction illustrated, the bottom 7 is carried by a frame having inwardly projecting flanges 13, vertical flanges 14 around its periphery, and an inwardly and downwardly extending portion 15 therebetween forming a recessed support. Hinge elements 16 are welded or otherwise secured to the bottom frame and hinge elements 17 are similarly secured to the lower portion of the end members 8. Also in this construction the end members 8 are shown as formed from solid metal sheets provided with a series of inwardly projecting vertical flanges 18 to which the side members 10 are pivotally secured as aforesaid by means of rivets or bolts at 11. The sloping sides 12 of the ends of the basket are recessed slightly between the inwardly projecting flanges 18 as shown in Fig. 2.

The side members 10 may be of any suitable construction and are here shown as rod-like members having flattened end portions 19 for convenient attachment to the vertical flanges 18 of the ends. The top edge of the end members 8 may be turned over to form a flange or bead 20 for reinforcement and to provide a smooth edge. The completed basket may be permanently secured to the top frame or shelf

of the carrier, or if desired may be removably carried thereon.

It will be observed that in the construction I have described the series of horizontal side members 10 are pivotally secured to the flanges 18 in different vertical planes as best illustrated in Fig. 2. It is this arrangement which makes it possible for the side members to be arranged in the overlapping position shown in Fig. 3 when the basket is collapsed, making an extremely compact unit.

In the modified construction illustrated in Figs. 4 to 6, the ends of the basket are built up of a series of flat parallel straps 21 riveted to supports 22 as at 23, these straps being of progressively greater length from bottom to top of the basket so that the sides of the basket ends incline upwardly and outwardly as in the construction previously described. The ends of the straps 21 are flanged inwardly as at 24. Horizontal side members 25 are pivotally secured to these flanged portions 24 as by means of the rivets 26. The side members may be reinforced by raised ribs 27 and the uppermost pair of side members in the construction shown are flanged outwardly and downwardly as at 28 to strengthen them and protect the user against sharp edges.

The lower ends of the supports 22 are bent inwardly as shown in Fig. 4 and terminate in a cylindrical portion 29 (Fig. 6) forming one element of a hinge. The other element 30 of the hinge is bolted to the frame 31 of the bottom which may be constructed in a manner similar to that which has been described with reference to Figs. 1 to 3 inclusive. The bottom 7 and members of the frame 31 may be secured together in any manner as by means of bolts 32. A hinge pin 33 passes through the elements 29 and 30 as shown in Fig. 5. Fig. 6 shows how the side members 21 nest together when the basket is in collapsed position so that the basket will take up a small amount of space. This is of particular importance when the basket is attached to

a folding carrier and permits the complete unit to be stacked closely with others.

The terms and expressions which I have employed are used in a descriptive and not a limiting sense, and I have no intention of excluding such equivalents of the invention described, or of portions thereof, as fall within the purview of the claims.

I claim:

1. A folding basket for market carriers comprising a bottom, like end members pivotally mounted in association with the bottom on pivots located above the plane of the bottom, said end members having side edges inclined upwardly and outwardly, a series of inwardly projecting vertical flanges along said inclined side edges, said vertical flanges being arranged in different vertical planes, and a series of horizontal side members pivotally secured to said vertical flanges in said different vertical planes.
2. A folding basket for market carriers comprising a bottom, like end members hingedly mounted in association with the bottom, said end members having side edges inclined upwardly and outwardly, a series of inwardly projecting vertical flanges along said inclined side edges, said vertical flanges being arranged in different vertical planes, and a series of horizontal side members pivotally secured to said vertical flanges in said different vertical planes, the side members being mounted on the outside of said flanges at both ends of the basket.

GEORGE W. CONCKLIN.
